TYPEWRITING AND LIKE MACHINES

Charles E. Smith, Tonawanda, N. Y., assignor to
Remington Rand Inc., New York, N. Y., a cor-
poration of Delaware

Application July 28, 1938, Serial No. 221,772

9 Claims. (Cl. 197—84)

My invention relates to typewriting and like machines for justifying typewritten lines, and more particularly to a means for facilitating the setting or adjustment of the justifying mechanism of such machine.

One of the main objects of my invention is to provide improved, highly efficient and reliable mechanism which greatly facilitates the setting or adjusting of the justifying mechanism so that in rewriting lines of unjustified copy they will be produced in justified lines of uniform length.

Another object of my invention is to provide means as specified above which may be readily embodied in a typewriting machine of standard construction without modifying or materially modifying the existing structure, and which is comparatively simple in construction, reliable and highly efficient in use and which may be manufactured at a comparatively small cost.

A further object of my invention is to provide in a typewriting machine having an escapement mechanism for affording variable extents of carriage movement, a means settable in accordance with the number of times the escapement mechanism will be actuated in rewriting a given line and in accordance with the total extent of change required in the length of the line to be justified, such means being operable to automatically predetermine the extent of carriage movement required at each actuation of the escapement mechanism to justify the line.

A still further object of my invention is to provide an improved setting or adjusting means as specified above in a justifying typewriting machine having a variable escapement mechanism for affording variable extents of carriage movement either above or below the normal extent of letter spacing, whereby the setting means is operable to automatically obtain the required extent of increase or decrease in the normal extent of carriage movement in recopying, to thereby justify a line when said means is set in accordance with the number of intermittent operations of the variable escapement mechanism in rewriting the line and in accordance with the total extent of increase or decrease in the length of the line required for justification.

To the above and other ends which will hereinafter appear, my invention consists in the features of construction, arrangements of parts and combinations of devices set forth in the following description and particularly pointed out in the appended claims.

In the accompanying drawing, wherein like

reference characters designate corresponding parts in different views:

Fig. 1 is a fragmentary front elevational view of a portion of a typewriting machine equipped with a setting or adjusting means constructed in accordance with my invention.

Fig. 2 is a fragmentary bottom plan view of a portion of the typewriting machine showing a variable escapement mechanism and a control or regulating means therefor constructed in accordance with my invention.

Fig. 3 is a sectional view of a portion of the setting means taken on line 3—3 of Fig. 1 and viewed in the direction of the arrows at said line.

Fig. 4 is a sectional view of another portion of the setting means taken on line 4—4 of Fig. 3 and viewed in the direction of the arrows at said line.

Fig. 5 is a sectional view of a portion of the control or regulating means for the variable escapement mechanism taken on line 5—5 of Fig. 2 and viewed in the direction of the arrows at said line.

I have shown my invention embodied, in the present instance in a No. 10 Remington Noiseless typewriting machine equipped with a justifying mechanism constructed substantially in accordance with my copending application Serial No. 97,225 filed August 21, 1936, now Patent No. 2,208,806, issued July 23, 1940, in which my invention may be readily embodied with but few changes in the existing structural features of said justifying mechanism. However, it should be understood that my present invention is not restricted to embodiment in such machine, nor is it restricted to use in combination with the justifying mechanism of my copending application, but may be employed in various other types of machines or in combination with other types of justifying devices as well, wherever found available.

I have shown in the accompanying drawing only so much of the usual structure of the No. 10 Remington Noiseless typewriting machine and the justifying devices of my copending application as is necessary to arrive at a complete understanding of my present invention in its embodiment therein.

My copending application Serial No. 97,225 discloses a justifying mechanism applied to a No. 10 Remington Noiseless typewriting machine which is operable to justify typewritten lines in recopying by varying the extent of spacing between words either above or below the extent of normal letter spacing and without modifying the ordi-

nary spacing between the letters of the words. I have herein applied my improved setting or adjusting mechanism to a justifying machine of this type, wherein the spacing between words only is varied, but as will hereinafter appear, my invention may be applied to other types of justifying devices, such for example as a type wherein the spacing between letters as well as the spacing between words may be varied throughout a line.

In my hereinbefore mentioned copending application, two independently operable escapement means are provided, one escapement means being under control of the printing keys to effect a normal letter space advance of the carriage, the other escapement means being under control of a space bar or a special word spacing key to effect an advance of the carriage in fractional amounts above or below the extent of a normal letter space, such fractional amount being predetermined by a manual adjusting means. The correct setting of this manual adjusting means is determined by dividing the number of letter spaces which the particular line must be expanded or contracted by the number of word spaces in the line.

In the construction disclosed in said copending application, it is necessary for the operator to calculate the extent of word spacing required for justification by actual division or by the use of a precalculated chart before setting the manual adjusting member which is graduated in terms of fractional extents of a letter space both above and below the extent of a normal letter space.

In accordance with my present invention, I propose to relieve the operator of the necessity of actually calculating the extent of word spacing required to justify a line by the provision of a manual adjusting means which may be set directly in accordance with the number of letter spaces which a line must be either expanded or contracted for justification and in accordance with the number of word spaces in the line, and which adjusting means coacts with the variable escapement mechanism to automatically obtain the extent of word spacing required for justification of that line, the same as would be arrived at by actual calculation on the part of the operator.

In the drawing, a portion of the frame of a No. 10 Remington Noiseless typewriting machine has been shown as including a right hand side plate 10 and a rear cross member 11. Only the parts of the escapement mechanism of my copending application which are directly associated with the setting or adjusting mechanism of the present invention have been shown in the drawings. The illustrated parts of this escapement mechanism include an escapement wheel 14 having comparatively fine teeth 15 as shown in Fig. 2.

In the present instance the escapement wheel 14 is provided for affording the spacing between words only and is accordingly connected to the carriage for control thereof jointly with another escapement mechanism for spacing between the letters of the words. In the specific arrangement of the escapement mechanism of my copending application, the usual feed rack mounted on the carriage coacts with a feed pinion mounted at the upper end of a substantially vertically disposed feed shaft. This feed shaft is connected by a differential or planetary gear to both the normal escapement wheel for affording letter spacing and also to the differential escapement wheel, such as 14 in the present drawing, for

affording variable extents of word spacing independently of the normal escapement wheel. However, it is sufficient for an understanding of the present invention to consider that the escapement wheel 14 shown in Fig. 2 is operatively connected to the carriage to afford an extent of spacing in proportion to the extent of rotation thereof as determined by the adjustable means shown in Fig. 2, for spacing between words only as in said companion application or generally for effecting differential spacing for justifying.

Referring to Fig. 2, it will be seen that the escapement wheel 14 is provided with a central hub portion 16 which rotates around a pivot screw 17 which is in axial alignment with the feed shaft of the machine. Actual operative connection between the escapement wheel 14 and the feed shaft is not shown in the present drawing but when employed for word spacing only may include planetary gearing arranged as shown and described in my copending application. However, if the variable escapement mechanism were to be used for spacing between the letters as well as the words throughout the line, the escapement wheel 14 could be directly connected to the feed shaft and controlled in the same manner as the normal escapement ordinarily employed in the machine.

A carrier arm 18 is mounted by an enlarged hub portion 19 for rotation concentrically with the escapement wheel 14 and anti-friction bearing balls 21 may be provided in an inner circumferential race in the hub member 19 and a companion race formed jointly by the hub 16 of the escapement wheel and a retaining ring 20. A spiral spring 22 secured at its inner end at 23 to a stationary bracket 24 acts on the carrier arm 18 through a pin 25 to return the carrier 18 to and hold it in its normal position shown in Fig. 2. The normal position of the carrier 18 is determined by the engagement of the extreme outer end thereof with an upstanding portion 26 at the forward end of an extension 26 of the cross member 11 of the frame of the machine.

The means for affording intermittent advance movement of the carriage through the escapement wheel 14 includes an anchor member 27 pivotally mounted at 28 to a stationary bracket 29 mounted on the machine frame. An extension 30 of the anchor member 27 may be connected by a pull rod 30a to the usual space key or to a special word spacing key or other actuating connection, whereby the anchor member 27 is rocked from its illustrated position in a counter-clockwise direction upon a depression for example, of the space key or said special key, and when the key is released the anchor member 27 is returned to its illustrated normal position by spring means not shown.

The anchor member 27 coacts with the escapement wheel 14 through a pair of feed dogs, one of which is a holding dog 32 formed at the left hand end of the anchor member 27 and normally entering an interdental space in the escapement wheel 14. The other feed dog is a stepping dog 33 normally out of the path of the teeth of the escapement wheel 14 and mounted on the carrier arm 18 for radial movement relative to the teeth 15 of the wheel 14. The stepping dog 33 may be mounted on the carrier arm 18 by a transverse portion 34 carrying grooved rollers 35 which receive at the grooved peripheries thereof the opposite edges of the carrier arm 18. A pin 36 attached to the stepping dog 33

extends downwardly through a slot (not shown) in the carrier arm 18, which pin 36 carries at the lower end thereof a roller 37 engaging the outer curved edge of an extension 38 of the anchor member 27. The stepping dog 33 is biased inwardly along the carrier arm 18 by an expansion spring 39 extending between an upstanding pin 40 at the outer end of the carrier arm 18 and the upstanding end of the pin 36 carried by the stepping dog 33.

It will now be clear that upon the depression of the usual space bar or the special word spacing key, or other actuating means for the escapement, the anchor member 27 will be rocked in a counter-clockwise direction, as the parts are shown in Fig. 2, to allow the stepping dog 33 to move inwardly along the carrier arm 18 under the force of the spring 39 to a position entering an interdental space in the escapement wheel 14, and the holding dog 32, by the same movement of the anchor member 27 will be withdrawn from the path of the teeth 15 of the escapement wheel 14.

As soon as the holding dog 32 is out of the path of the teeth 15, the force of the usual carriage spring drum (not shown) starts to turn the escapement wheel 14 in a clockwise direction as viewed in Fig. 2, and the carrier arm 18 being connected to the escapement wheel 14 through the stepping dog 33 turns therewith in a clockwise direction. During this movement of the carrier arm 18 and the stepping dog 33 in unison with the escapement wheel 14, the roller 37 rides along the outer edge of the arm 38, which is on an arc centered about the axis of the escapement wheel 14 when the anchor member 27 is in its operated position.

The escapement mechanism thus far described may be the same as disclosed in my copending application and need not be modified in any respect by the incorporation therewith of the devices of the present invention. In accordance with my copending application as well as in accordance with the present invention, a stop means is provided for predetermining various extents of clockwise movement of the carrier arm 18 in unison with the escapement wheel 14 to accordingly predetermine the extent of advance movement of the carriage in spacing which will be afforded at each operation of the anchor member 27. The present invention is directed particularly to the arrangement of such adjustable stop member for determining the extent of movement of the carrier member 18 together with means for facilitating the setting of this adjustable stop member to obtain the required extent of carriage spacing movement to justify various lines.

It may be generally described at this point that the adjustable stop member of the present invention comprises a disc 45 having a plurality of stop faces, one of which stop faces, according to its rotated position, is engaged by a pin 46 on the carrier arm 18 to thereby determine the extent of clockwise rotation of the arm 18 and the escapement wheel 14 at this time effectively connected thereto when the anchor member 27 is operated. The specific arrangement of the stop faces on the disc 45 will be later described in detail as the arrangement of these stop faces is determined to a large extent by the design of the manual setting means to be hereinafter referred to.

Referring to Fig. 5, it may be seen that the stop disc 45 is mounted on a hub 48 which ex-

5 tends downwardly through a bearing opening in a retaining bracket 49, which bracket may be formed integrally with the cross member 11 of the machine frame. The stop disc 45 may be retained in its bearing opening in the member 49 by a collar 50 placed between the upper surface of the cross member 11 and the bracket 49 and secured to the hub 48 by a screw 51.

10 The stop disc 45 thus rotatively mounted on the cross member 11 is operatively connected with the manual setting means through a suitable flexible shaft or cable 53 arranged to turn within an outer flexible sheath 54. Thus as shown in Fig. 5, an opening is provided in the cross member 11 in axial alignment with the hub 48 which opening receives the sheath 54 which is retained therein by a screw 55. The inner flexible cable 53 extends upward through the cross member 11, and the upper end thereof is soldered or otherwise suitably secured within an opening in the lower end of the hub 48.

15 The sheath 54 carrying the flexible cable 53 extends from the lower side of the rear cross member 11 forward and upward within the machine frame to a position in the rear of the right hand end of a front plate 58 which is ordinarily provided on the machine. The flexible cable may be held against lateral displacement from the side plate 10 by suitable clips 56 secured to the side plate 10 to partially surround the sheath 54. The upper and forward end of the flexible sheath 54 terminates in an opening in a member 60 extending to the left from the side plate 10 in the rear of the front plate 58. The inner end of the member 60 may be split along the opening receiving the sheath 54, as shown in Fig. 4, with upturned ear portions 61 carrying a clamping screw 62 whereby the sheath 54 may be securely clamped within the end of the member 60.

20 Referring now to Fig. 3, the forwardly extending end of the flexible shaft 53 is soldered or otherwise suitably secured within an opening (not shown) in a shouldered portion 65 of a short shaft 66, which shaft extends forward through an opening in the front plate 58 of the machine. The shoulder 65 of the shaft 66 engages the rear surface of the front plate 58, and the forward end of the shaft 66 enters an opening in a hub 67 and is retained therein by a screw 68. The hub 67 is surrounded by a finger piece or knob 69 which is provided with a flange or dial 70. A substantially semi-circular dial plate 72 is attached by screws 73 to the front plate 58 of the machine at a position to surround the upper half of the outer edge portion of the dial 70.

25 From the foregoing description, it will be clear that the knob 69 and its dial 70 is positioned on the front plate 58 of the typewriting machine for convenient manipulation by the operator, and this knob is connected through the flexible cable 53 to the stop member 45, whereby the operator may conveniently turn the stop member 45 to various positions of adjustment by merely turning the knob 69.

30 In a justifying mechanism employing a variable escapement mechanism, it will be clear that the change from normal spacing which is to be afforded by said variable escapement mechanism to justify any particular line will be determined by two factors, one of these factors being the extent of change of length of the line required for justification, the other factor being the number of intermittent operations of the variable escapement mechanism in writing the line. It is usually convenient to reckon the

total extent of change of length of a line required for justification in terms of letter spaces, and when the variable escapement mechanism is to be used for spacing between words only, it is convenient to reckon the total number of intermittent operations of such escapement mechanism in typing a line in terms of word spaces.

Thus in accordance with the present invention, the setting of the adjustable stop member 45 is facilitated by cooperating scales on the movable dial 70 and the fixed dial plate 72, one scale having numeral indices thereon representing the extent of change of length required in a line in terms of character spaces, the other scale having numeral indices thereon designating the number of intermittent operations of the variable escapement which in the instance shown in the drawing is in terms of word spaces. Although it is immaterial which of these two cooperating scales is placed on the movable dial 70 and which is placed on the fixed dial plate 72, it has been elected for the present disclosure to place the scale representing the various numbers of character spaces on the movable dial 70 to cooperate with the other scale representing the various numbers of word spaces on the fixed dial plate 72. In order to avoid confusion in the use of these two cooperating scales, the term "word spaces" is suitably marked on the face of the dial plate 72, and the term "character spaces" is marked on the face of the dial 70. It should be understood however, that these markings may be modified to suit the requirements of different characters of justifying mechanism, as hereinafter pointed out.

The escapement mechanism to which the devices of the present invention are applied is operable to either expand or contract the length of the line for purposes of justification, and for convenience in the present disclosure, it has been elected that the range of adjustment should afford either an expansion in the length of a line to any extent from one to five letter spaces, or a contraction in the length of a line to any extent from one to five letter spaces. However, neither the escapement mechanism nor the setting means is limited to this particular range of adjustment. The range of variation in the number of word spaces in the various lines has also been arbitrarily selected from five to fifteen, and it also should be understood that this range of variation may be varied if desired.

Inasmuch as the present justifying mechanism is operable to either expand or contract the length of a line, there are in the present instances, two substantially duplicate scales provided on both the movable dial 70 and the fixed dial plate 72, one scale on each of the members being designated by the term "expand" and the other scale on each of the members being designated by the term "contract." Thus the "expand" scale on the movable dial 70 is provided with numerals from "1" to "5" progressing in a counter-clockwise direction and placed opposite scale divisions which are spaced or graduated according to the logarithms of these numbers. The "contract" scale on the movable dial 70 is provided with numerals from "1" to "5" placed opposite scale divisions which are spaced or graduated according to the logarithms of these numbers the same as on the "expand" scale, but in this case the numerals progress from "1" to "5" in a clockwise direction.

A very similar arrangement is provided on the fixed dial plate 72, wherein the "expand"

scale is provided with numerals from "5" to "15" progressing in a counter-clockwise direction and placed opposite scale divisions which are spaced or graduated according to the logarithms of these numbers. The "contract" scale on the dial plate 72 is provided with numerals from "5" to "15" placed opposite scale divisions which are spaced or graduated according to the logarithms of these numbers the same as the "expand" scale, but in this case, the numerals progress from "5" to "15" in a clockwise direction.

In using the present setting means, the "expand" scale on the movable dial 70 cooperates only with the "expand" scale on the dial plate 72, and likewise the "contract" scale on the dial 70 cooperates only with the "contract" scale on the dial plate 72. Accordingly it may be found desirable to provide the markings on the "expand" scales of each of the members 70 and 72 in a color which contrasts with the color of the markings of the "contract" scales thereon.

Inasmuch as it may sometimes be desirable to set the escapement mechanism to neither expand nor contract a line, a "0" position is indicated on the dial 70 which is associated with a "0" position on the dial plate 72. When the "0" point on the movable dial 70 is placed in register with the "0" mark on the dial plate 72 as shown in Fig. 1, the stop plate 45 is positioned as shown in Fig. 2, wherein a stop face 75 thereon is in the path of the stop pin 46 of the carrier arm 18 as it is operated in a clockwise direction from its illustrated normal position. The stop face 75 is positioned at such a distance from the center of the stop disc 45 that the escapement wheel 14 travels a distance before it is arrested by the engagement of the stop pin 46 therewith to afford exactly one normal letter space advance movement of the carriage.

In the present instance it may be assumed that, as in my said companion application, the escapement wheel 14 is so connected with the carriage that a 48 degree rotation thereof affords exactly one normal letter space advance movement of the carriage, and ten teeth of the escapement wheel are provided in the 48 degree sector through which it rotates to afford one normal letter space movement. Thus, seventy-five teeth are provided throughout the entire circumference of the escapement wheel 14. Inasmuch as the variation in the distance through which the carrier arm 18 is allowed to travel is necessarily in multiples of the teeth of the escapement wheel 14, the variation in spacing which may be afforded by the present mechanism will be in multiples of one-tenth part of a normal letter space.

In order to illustrate the operation of the present mechanism it will first be considered that it is desired to expand the length of an unjustified line to the extent of one letter space distance, which line has ten word spaces. The operator in this instance turns the movable dial 70 by the knob 69 in a clockwise direction from its illustrated position in Fig. 1 to a point where "1" on the "expand" scale on the dial 70 registers with "10" on the "expand" scale on the dial plate 72. This clockwise direction of rotation of the movable dial 70 turns the stop plate 45 in a clockwise direction as viewed in Fig. 2 to such an extent that a stop face 76 thereon is brought into the path of the stop pin 46 of the carrier arm 18. Or more specifically the radial dotted line a intersecting the stop face 76 in the

drawing indicates the point on the stop face 76 which will be engaged by the stop pin 46 when the dial 70 is moved to the above described position.

It will be noted in Fig. 2 that the radius of the stop face 76 is sufficiently shorter than the radius of the stop face 75 that when the stop face 76 is in the path of the stop pin 46 the carrier arm 18 is allowed to travel one additional tooth space distance, or a distance equal to eleven tooth spaces on the escapement wheel 14. Thus, it will be clear that when the dial 70 is moved to a point wherein "1" on the "expand" scale thereof registers with "10" on the "expand" scale on the dial plate 72, the stop plate 45 is moved to a position which affords one and one-tenth times a normal letter space. It will be clear that this extent of spacing between each of the words in a line having ten interword spaces will expand such a line to an extent of one normal letter space in retyping for justification, which is in accordance with the setting of the dial 70.

Likewise it will be clear that if it is desired to expand a line also having ten word spaces to the extent of two normal letter spaces, the operator turns the movable dial 70 farther in a clockwise direction to a position wherein "2" on the "expand" scale of the dial 70 registers with "10" on the "expand" scale of the dial plate 72. This positions the stop plate 45 so that stop face 77 is in the path of the stop pin 46, and as the stop face 77 is formed on a still shorter radius than the stop face 76, the carrier arm 18 will travel through a distance equal to twelve tooth spaces of the escapement wheel 14. Thus the extent of word spacing afforded at this setting of the dial 70 will be equal to one and two-tenths times a normal letter space, thereby expanding the length of the line to the extent of two normal letter spaces in retyping for justification.

In a very similar manner, a line having ten word spaces may be expanded to the extent of three, four or five character spaces by moving the dial 70 farther in a clockwise direction so that the associated numeral index on the "expand" scale of the dial 70 is in register with "10" of the "expand" scale of the dial plate 72. In case the dial 70 is set to expand such a line to the extent of three character spaces, the stop plate 45 will be positioned so that a stop face 79 thereof is disposed in the path of the stop pin 46 of the carrier 18, the radius of the stop face 79 being such that the carrier 18 moves a distance equal to thirteen tooth spaces of the escapement wheel 14. This affords one and three-tenths times a normal letter space between each of the words of a line, and a line having ten interword spaces will accordingly be expanded in length to the extent of three normal letter spaces. When "4" or "5" is placed in register with "10" as mentioned above, a stop face 79 or a stop face 80 respectively of the stop member 45 will be placed in the path of the stop pin 46. The stop faces 79 and 80 are arranged to afford a fourteen tooth and a fifteen tooth movement respectively of the escapement wheel 14, and accordingly an expansion in the length of a line having ten interword spaces to the extent of four or five character spaces may be respectively attained thereby in a manner which will be obvious from the previous descriptions of

the methods of obtaining lesser extents of expansion.

In the drawing, the broken radial lines *a* intersecting the stop face 76 and the radial lines *b* intersecting the companion stop faces 77, 78, 79 and 80 indicate the respective points on the stop plate 45 which will be engaged by the stop pin 46 when the numeral indices "1," "2," "3," "4" and "5" are placed in register with "10" of the "expand" scale on the dial plate 72.

The above specific instances of the setting of the stop plate 45 are all for lines having ten interword spaces, but it will be clear that if a line has a larger or a smaller number of interword spaces, the proper numeral index on the "expand" scale of the dial 70 will be placed in register with a different index on the "expand" scale of the dial plate 72. In this manner a different position of the stop plate 45 is obtained for any given extent of expansion of a line depending on the number of interword spaces in the line, and the arrangement of the cooperating scales on the dial 70 and dial plate 72 is such that the stop plate 45 will be positioned in each instance to obtain the exact extent of movement of the escapement wheel 14 required to justify the line or the nearest approach to such an exact movement thereof which can be afforded by the particular variable escapement mechanism.

For example, if it is desired to expand a line to the extent of one character space which line has five interword spaces rather than ten as described above, "1" on the "expand" scale of the dial 70 is placed in register with "5" on the "expand" scale of the dial plate 72, thereby positioning the stop plate 45 so that stop face 77 is engaged by the stop pin 46. This affords a twelve tooth movement of the escapement wheel 14 rather than an eleven tooth movement as afforded by the stop face 76 which is positioned in the path of the stop pin 46 when a line having ten interword spaces is to be expanded to the extent of one character space. It will be clear that a twelve tooth movement of the escapement wheel 14 will expand the length of a line having five interword spaces to the extent of one character space. In the above instance when "1" on the "expand" scale of the dial 70 registers with "5" of the "expand" scale on the dial plate 72, it will be clear that due to the logarithmic arrangement of the numerals on the two cooperating scales, the numerals "2" and "3" on the "expand" scale of the dial 70 will also register with the numerals "10" and "15" respectively on the "expand" scale of the dial plate 72. In other words, the two expansion scales on the members 70 and 72 cooperate in a very similar manner to two cooperating scales of a slide rule.

It was previously pointed out that the two cooperating "contract" scales on the members 70 and 72 are substantially the same as the "expand" scales just described except for the reverse arrangement thereof, and accordingly it is believed that the specific details of the cooperation between these "contract" scales need not be described. However, the control of the stop plate 45 by the two "contract" scales may be generally described by pointing out that if "1," "2," "3," "4" and "5" on the "contract" scale of the dial 70 are successively placed in register with "10" on the "contract" scale on the dial plate 72, stop faces 81, 82, 83, 84 and 85 will be successively positioned in the path of the stop pin 46, and

the broken radial lines **c** intersecting these stop faces on the drawing indicates the points thereon which will be engaged by the stop pin at each of such successive positions of the stop member **45**.

The distances from the various stop faces **81** to **85** to the axis of the stop plate **45** are so varied that nine, eight, seven, six and five tooth spaces of movement of the escapement wheel **14** are respectively afforded when the corresponding stop face is positioned in the path of the stop pin **46**. Thus, the various extents of movement of the escapement wheel **14** afforded by the stop faces **81, 82, 83, 84** and **85** will result in the contraction of the length of a line having ten interword spaces to the extent of one, two, three, four and five character spaces respectively in accordance with the setting of the dial member **10**. It is believed that the method in which the two cooperating "contract" scales on the members **10** and **12** function to select a position of the stop member **45** which will contract a line to various extents having other than ten interword spaces will be obvious in view of the previous description of the function of the "expand" scales.

The stop member **45** is arranged in the present instance to afford a variation in the word spacing from one-half of a normal letter space to one and one-half times a normal letter space, and due to the specific arrangement of the present variable escapement mechanism, the variation of the word spaces within this range is in multiples of one-tenth part of a normal letter space. Thus, it will be clear that whenever the quotient resulting from the division of the number of character spaces of expansion or contraction in the line length by the number of word spaces in the line is a multiple of one-tenth part of a normal letter space, the stop member **45** functions to select the exact extent of word spacing required for justification. However, in other instances wherein the required extent of word spacing for justification is not a multiple of one-tenth part of a normal letter space, an extent of word spacing is automatically selected by the stop member **45** which is a multiple of one-tenth part of a normal letter space approaching closest to the exact extent of word spacing required for justification. In other words, the divisions or steps between the various stop faces of the stop member **45** are positioned in each instance so that the setting of the dial **10** will select either the exact extent of word spacing required for justification or the closest approach thereto which can be obtained on the particular design of the variable escapement mechanism with which the setting mechanism cooperates.

From the above, it will be clear that in order to set or adjust a justifying typewriting machine equipped with the devices of my invention, the operator merely moves the dial **10** to a point where a numeral index thereon corresponding to the extent of increase or decrease in the length of the line required for justification registers with a numeral index on the dial plate **12** representing the number of word spaces in the line, and this dial **10** then operates through the stop member **45** to automatically obtain the required extent of increase or decrease in the normal extent of spacing between the words of the line to justify that particular line. Thus, the operator is entirely relieved of calculating the required extent of increase or decrease in each word space to justify the line, which not only saves time and effort on the part of the operator, but also

tends to promote a greater accuracy in justification by eliminating the possibility of erroneous calculation or adjustment.

Although my setting or adjusting mechanism **5** of the present invention has been shown and described in connection with a variable escapement mechanism such as is disclosed in my said companion application which is employed for spacing between words only, a setting or adjusting mechanism **10** operating on the same principle may be applied to other types of justifying mechanism, such for example as the type wherein a variable escapement mechanism is provided for spacing between the letters as well as the spacing between **15** the words throughout the line. For example, if the variable escapement mechanism illustrated in the present drawing were to be employed to space between the letters as well as the words of a line, substantially the same setting means could be **20** employed by making obvious changes in the numeral indices and the legend on the dial plate **12**, as well as any changes in the specific profile of the stop member **45** which may be required. In other words, the numeral indices on the dial **25** plate **12** would in this case denote various lengths of lines either in terms of inches or in terms of the total number of letter spaces and word spaces. However, it will be clear that regardless of whether the present setting means is **30** employed in connection with a variable escapement mechanism for spacing between words only or for spacing between the letters as well as the words throughout the line, the numeral indices on the scales of the dial plate **12** will denote various **35** numbers of intermittent operations of the variable escapement mechanism, which as previously pointed out, is one of the factors in determining the extent of change from normal spacing to justify each line.

In the illustrated embodiment of the present invention, the setting or adjusting means has been shown and described in connection with a variable escapement mechanism for spacing between words only and it has been described that a normal escapement mechanism under control of the printing keys is to be provided for affording uniform letter spacing. However, it will be understood that the devices of the present invention may equally well be employed in combination with an escapement mechanism for affording variable letter spacing to accord with different widths of printed characters. If such a variable letter spacing mechanism is employed in combination with the variable word spacing escapement mechanism, the increase or decrease required in the length of a line for justification may be reckoned in terms of a unit which is a divisor of all of the various units of letter spacing and the numeral indices on the movable dial **10** may be accordingly arranged.

It is also to be understood that the devices of the present invention could be employed in various other characters of typewriting machines, and in referring to a "carriage" in the foregoing description and in the appended claims, it will be understood that such term is employed in a generic sense to apply to flat platen machines wherein the printing instrumentalities are carried by and travel with the carriage, as well as the platen carrying carriage of the type herein referred to, unless that "carriage" be otherwise more specifically defined.

It is also to be understood that in the foregoing description, an attempt has not been made to point out all the alternate or optional features

of construction that may be employed and that various modifications, adaptations and alterations may be applied to meet the requirements of practice and some parts of the construction may be employed without others without departing from my invention as it is defined in the accompanying claims.

What I claim as new and desire to secure by Letters Patent is:

1. In a typewriting machine for justifying typewritten lines, the combination of a variable escapement mechanism having adjustable regulating means for affording various extents of spacing between words, and manual setting means comprising cooperating fixed and movable scales having indices on one scale designating the number of word spaces in a line and having indices on the other scale designating the number of character spaces of expansion and the number of character spaces of contraction in the length of the line that may be required for justification, and means operatively connecting said movable scale with said regulating means. 10
2. In a typewriting machine for justifying typewritten lines, the combination of a variable escapement mechanism having adjustable regulating means for affording various extents of spacing between words, and manual setting means comprising cooperating fixed and movable scales having numerals on one scale designating the number of word spaces in a line and having numerals on the other scale designating the number of character spaces of expansion and the number of character spaces of contraction in the length of the line that may be required for justification, said scales being graduated to the logarithms of the numerals thereon, and means operatively connecting said movable scale with said regulating means. 20
3. In a typewriting machine for justifying typewritten lines, the combination of a variable escapement mechanism having adjustable regulating means, and manual setting means comprising one pair of cooperating fixed and movable scales having indices on one scale thereof designating the number of word spaces in a line and indices on the other scale thereof designating the total extent of expansion in the length of the line required for justification, and another pair of cooperating fixed and movable scales having indices on one scale thereof designating the number of word spaces in a line and indices on the other scale thereof designating the total extent of contraction in the length of the line required for justification, and means operatively connecting said movable scales with said regulating means. 30
4. In a typewriting machine for justifying typewritten lines, the combination of a variable escapement mechanism having adjustable regulating means, and manual setting means comprising one pair of cooperating fixed and movable scales having numerals on one scale thereof designating the number of word spaces in a line and numerals on the other scale thereof designating the total extent of expansion in the length of the line required for justification, and another pair of cooperating fixed and movable scales having numerals on one scale thereof designating the number of word spaces in a line and numerals on the other scale thereof designating the total extent of contraction in the length of the line required for justification, both of said pairs of cooperating fixed and movable scales being graduated to the logarithms of the numerals thereon, and said movable scales being operatively connected to said regulating means. 40
5. In a typewriting machine for justifying typewritten lines, the combination of a variable escapement mechanism having rotatable regulating means, a manually rotatable dial directly connected to said regulating means, a stationary dial plate cooperating with said rotatable dial, and means to aid in setting said rotatable dial comprising one set of cooperating logarithmic scales on said rotatable dial and on said dial plate cooperative for the setting of said rotatable dial to afford expansion in the length of a line and another set of cooperating logarithmic scales on said rotatable dial and on said dial plate cooperative for the setting of said rotatable dial to afford contraction in the length of a line. 50
6. In a typewriting machine for justifying typewritten lines, the combination of a variable escapement mechanism having regulating means therefor, a movable member connected to said regulating means, a stationary member cooperating with said movable member, and means to aid in setting said movable member comprising one set of cooperating logarithmic scales on said movable member and on said stationary member cooperative for the setting of said movable member to afford expansion in the length of a line, and another set of cooperating logarithmic scales on said movable member and on said stationary member cooperative for the setting of said movable member to afford contraction in the length of a line. 60
7. In a typewriting machine for justifying typewritten lines, the combination of an escapement mechanism including an adjusting means, controlling means for said escapement mechanism, and setting means including cooperating fixed and movable scales having numerals on one scale designating the number of operations of said controlling means in typing a line and numerals on the other scale designating the extent of increase or decrease in the length of the line required for justification, said movable scale being operatively connected to said adjusting means. 70
8. In a typewriting machine for justifying typewritten lines, the combination of an escapement wheel, a fixed dog cooperating with said escapement wheel, a dog carrier mounted to turn variable distances around the axis of said escapement wheel, a stepping dog mounted on said carrier for rectilinear movement thereon into and out of engagement with said escapement wheel, means for alternately operating said fixed dog and said stepping dog into and out of engagement with said escapement wheel, a pivoted stopping member having a plurality of stop faces spaced at different radial distances thereon to determine the extent of movement of said carrier when the stepping dog is in engagement with said escapement wheel by impact of said carrier against one of said stop faces substantially on dead center of the pivot of the stopping member, and manual setting means for obtaining the extent of movement of the carrier required to justify a line, said setting means including cooperating fixed and movable scales having graduations on one scale designating the number of intermittent operations of said dogs in writing the line and having graduations on the other scale designating the required total extent of change in length of the line, and means operatively connecting said movable scale with said stopping member. 80

9. In a typewriting machine, the combination of a variable escapement mechanism having adjustable regulating means, and setting means for said regulating means comprising cooperating fixed and movable scales having graduations on one scale designating various numbers of opera-

tions of said escapement mechanism and graduations on the other scale designating various extents of expansion and contraction in the length of typewritten lines, said movable scale being operatively connected with said regulating means.

CHARLES E. SMITH.
